General description. An improved Goodyear welt, or extended edge welt, having a thin, relatively soft, turned back flap, and a thick, relatively hard, extended out-seam flap, the latter being formed by the removal of a portion of the body of the welt, and having a relatively thick, relatively hard, turned back flap, and a relatively thin, relatively soft, extended out-seam flap, the latter being formed by the removal of a portion of the body of the welt.

UNITED STATES PATENT OFFICE

GOODYEAR WELTING

James W. Spence, Rockland, Mass.

Application April 14, 1931, Serial No. 529,945

9 Claims. (Cl. 36—78)

The present invention relates to an improvement in Goodyear welting.

The welting used in the manufacture of Goodyear shoes is ordinarily a strip of leather with a groove cut in the flesh side near one edge to receive the inseam by which the insole, lining, upper and welt are united. The sole is united to the welt by the outseam which is sewed through the opposite edge of the welt from the inseam groove.

10 The cost of welting is determined in large part by the thickness of the welt.

The object of the present invention is to produce an improved form of welting in which the thickness of the outer edge of the welt is increased 15 without increasing the thickness of the leather from which it is made. The invention consists in the Goodyear welting hereinafter described and particularly defined in the claims.

15 In the accompanying drawing illustrating the invention, Fig. 1 is a perspective view of a piece of welting embodying the preferred form of the invention; Fig. 2 is a similar view of a modified form of welting embodying the invention, and Fig. 3 is a cross-section of a strip of welting showing the method of cutting the welting to produce 20 the form of welt shown in Fig. 2.

The invention is described as follows: In the preferred form (Fig. 1) a welt strip of leather is split or slashed at the edge, which is to be the 25 groove edge of the welt, with an incision parallel to the top and bottom surfaces of the welt. Then the flap formed by the incision is turned back on the body of the welt and cemented thereto, after which the welting is grooved and beveled, as 30 shown, for the inseam stitches. The body 10 of the welt is slashed or split on the plane indicated by the line 11, starting from the groove edge of the welt and extending inwardly about half of the width of the welt. The thickness of this flap 35 will be less than that of the body of the welt remaining after the flap is removed. Then the flap 12 is turned over in the position shown in Fig. 1, and cemented on the line 13 to the body of the welt 10. The resulting welt strip is therefore 40 thicker than the original substance of the outer portion by an amount equal to the thickness of the flap cut from the body of the welt by the slash or slit in the groove edge thereof. The shoe sole is sewed by the out-seam to the outwardly extended portion of the welt (the left-hand portion as viewed in Fig. 1), the threads of the out-seam 45 extend through the welt and the turned back flap and through the sole of the shoe.

The modified form of the invention shown in 50 Fig. 2 is one in which the welt body is doubly

slotted to form an extended flap. In making this form of welt, the body of the welt 20 is slotted by an angular slit 21 and a straight slit 22. These two slits are united at the edge of the welt at 23, and after the slits are cut in the welt, this two-layer flap is flattened out, as shown at 24, and cemented to the body 20 of the welt.

In this modified form of the invention, the flap is made of two portions of the welt, united together at their ends, and they are thus folded out over the out-seam receiving portion of the body of the welt to serve to increase its thickness and therefore to enhance its value. Thus, if the original leather of which the welt is made were, say $\frac{3}{2}$ of an inch thick and the flap were cut $\frac{1}{2}$ of an inch thick, the resulting out-seam portion of the welt would be $\frac{1}{8}$ or $\frac{1}{2}$ of an inch thick, thereby increasing its thickness $33\frac{1}{3}\%$ and enhancing its value as a welt, not a full $33\frac{1}{3}\%$, but to an increased amount. The cost of the operations necessary to be performed in making this welting is somewhat greater than that of making ordinary solid welting, but such cost is less than the increased value of the welt after the operation has been performed on it and the finished welting is produced.

The preferred form of the invention (Fig. 1) is adapted for the general run of Goodyear welting including close edge welts. The modified form (Fig. 2) is adapted for wide welts including extension edge welts. Both forms of the invention produce a welt of a given thickness from leather of less thickness, thereby reducing the cost of the welting.

Another feature of this invention resides in the fact that the inseam portion of the welt, being thinner than the main body of the welt, conduces to the making of a better inseam, as the inseam portion of the welt being thinner than the body of the welt, bends to fit itself to the insole and upper more easily and thereby secures a tighter and stronger inseam.

A welt made in the section shown in Figs. 1 and 2, or substantially that form, may be made of a single piece of leather and still have substantial advantages over the ordinary uniform thickness welting. Thus, with a welting having an out-seam portion $\frac{3}{2}$ of an inch thick, the inseam portion may be reduced in thickness, say, to $\frac{1}{2}$ or $\frac{1}{3}$ of an inch, and grooved for the inseam on the side opposite the exposed side of the welt. Then when the inseam is sewed, the thinner portion of the welt is turned up and united to the upper, lining and insole. The reduction of the thickness of the inseam portion of the welt

is accomplished by slitting off a layer of this portion of the welt $\frac{1}{2}$ or $\frac{2}{3}$ of an inch thick. The strip of removed stock has a market value for other purposes, besides enhancing the value of 5 the welt. This shape of welt facilitates the inseam sewing operation by removing the otherwise cumbersome thick edge inseam portion of the welt and makes the inseam portion of the welt fold longitudinally with ease to closely embrace 10 the inseam thread in the groove.

What is claimed is:

1. A Goodyear welt having an outseam edge portion and an inseam edge portion, the outseam edge portion being thickened and the inseam edge portion being reduced by the transfer 15 to the former from the latter of a portion thereof, a shoulder between the outseam and inseam edge portions, the latter having an inseam groove cut in the same surface of the welt from which the 20 shoulder projects and at a distance from said shoulder.

2. A Goodyear welt slashed at the groove edge with an incision parallel to one surface of the 25 welt to form a flap, said flap being folded longitudinally of the welt back upon the surface of the unslashed portion and cemented thereto, and the portion from which the flap was cut being provided with a groove on the surface from which 30 the flap was separated.

3. A Goodyear welt slashed at the groove edge with an incision parallel to one surface of the 35 welt and folded longitudinally of the welt back upon the surface of the unslashed portion to form a thicker and a thinner portion, said thinner portion having an inseam groove in the surface formed by said incision.

4. The method of forming a Goodyear welt 40 which comprises slashing the groove edge with an incision parallel to the bottom surface of the welt, folding the resulting strip longitudinally of the welt back upon the unslashed portion of the body of the welt, cementing the folded strip thereto, and cutting an inseam groove in the 45 incised surface of the thinner portion of the welt at a distance from the fold between the strip and the body of the welt.

5. The method of forming a Goodyear welt with thick and thin portions which comprises forming incisions parallel to the bottom surface, folding the resulting strips longitudinally of the welt back upon the body of the welt, so that the thicker portion of the welt will be of greater width than the thinner, and cementing the folded strips in place. 80

6. The method of forming a Goodyear welt with thick and thin portions which comprises slashing the grooved edge to form two strips, forming an angular incision in one of the resulting strips to form two parallel flaps connected together at the grooved edge, aligning the flaps to increase the width of the strip from which said flaps were formed, folding the strip so formed back upon the body of the welt, and cementing the strip in place. 85

7. A Goodyear welt having an outseam edge portion and an inseam edge portion, both of said portions having a grain surface all in the same plane and the inseam edge portion being of reduced thickness and being provided with a thread receiving groove on the non-grain surface spaced from the portion of the welt of unreduced thickness to provide a flexing portion between the groove and the unreduced portion to facilitate the bending of the inseam portion of the welt. 90

8. A Goodyear welt slashed at the groove edge with an incision parallel to the bottom surface 100 of the welt to form a flap, said flap being folded longitudinally of the welt back upon the non-grain surface of the unslashed body of the welt, and cemented to increase the thickness of the unslashed body. 105

9. The method of forming a Goodyear welt which comprises slashing the groove edge with an incision to form a flap, folding the resulting flap longitudinally of the welt back upon the non-grain surface of the unslashed portion of the 115 welt throughout the width thereof, and cementing the folded strip thereto to increase the thickness of the unslashed portion of the welt. 110
